METHOD OF AND MEANS FOR CHARGING
TERMINAL POTHEADS WITH INSULATING
MATERIALAlfred Morris Thomson, Newark, N. J., assignor
to Dardel Threadlock Corporation, New
York, N. Y., a corporation of Delaware

Application August 14, 1930. Serial No. 475,323

8 Claims. (Cl. 247—1)

Important objects of the present invention are to provide an electrical connecting and insulating device, known as a "terminal pothead" filled with improved molded insulation free from air spaces or bubbles to more effectually insulate the enclosed electrical conductors; to provide for the charging of such a device with insulating material in a molten state while effectually excluding air and thereby prevent air spaces in the insulation; to provide for the exhaustion of air from the casing of the device preparatory to receiving the charge of molten material and also prevent the entrance of air along with the molten material; to prevent the escape of the molten material through the air exhausting connection; and to provide a satisfactory apparatus for attaining these ends.

In the drawings,

Fig. 1 is a side view of a pothead connected partly in section, upon a larger scale, and showing and means for exhausting air from its casing and means for charging the casing with molten insulation;

Fig. 2 a fragmentary side view of the pothead partly in section, upon a larger scale, and showing the first stage of the charging or pouring operation;

Fig. 3 a detail section taken on the line 3—3 of Fig. 2;

Fig. 4 a sectional view of the pothead fully charged with the molten insulating material; and

Fig. 5 a fragmentary sectional view of the charged pothead with its air exhaustion port and its charging port closed.

The pothead structure includes a cast iron casing or bell 1 of elbow form, having two open ends at right angles to each other, and enlarged at one end. At one side said casing is formed with brackets 2 for attachment to a support. The larger end of the casing is directed upward in the present instance and is closed by a cap 3. A gasket 4 is interposed between said cap and the casing end and a depending flange 5 formed on the cap surrounds the gasket and a narrow edge flange formed on the casing. Cap screws 6 are passed through ears 7 formed on the cap and are threaded into ears 8 formed upon the casing, to detachably hold the cap in place and clamped against the gasket.

Mounted upon the cap 3 are a plurality of tubular porcelain insulators 9. In the present instance there are three insulators, and, for supporting them, the cap is formed with bosses 10 each having a threaded aperture opening into the interior of the casing. A threaded ring or

sleeve 11 of drawn brass is screwed into the aperture of each boss and is formed with a flange abutting the outer end of the boss. The insulator supported by each boss has its lower end extending through sleeve 11 and into the casing and an abutment flange is formed on the insulator and bears against said flange of the sleeve. Between the sleeve and the inserted end of the insulator there is an annular space which is filled with cement 12. Thereby the insulators are rigidly held to the cap 3 and their connections with the latter are closed and sealed airtight. Each insulator is formed with a plurality of encircling flanges or skirts formed to shed water.

The electrical conductors or cables designated 13, lead to the casing through a pipe 14, preferably of galvanized iron, and enter the smaller end of the casing. Pipe 14 is joined to the casing end through the medium of a connecting sleeve 15. The latter is formed around one end with a flat outwardly extending flange 16 which is opposed to a flat inwardly extending flange 17 formed on the casing end. A gasket 18, preferably of vellumoid, is interposed between said opposed flanges and the latter are clamped against the gasket by cap screws 19. The opposite end of the connector sleeve is cup shaped to receive the pipe and has a threaded connection 20 therewith. The conductors 13 are individually sheathed with insulation and the group of conductors is wrapped with suitable insulation 52 and enclosed by a tubular sheathing 21 of lead which extends through the pipe 14 and the sleeve 15 and into the casing. Said tube is drawn and compressed about the enclosed insulated conductors so that the latter have an airtight fit within the tube. At its flanged end the sleeve 15 is formed with a threaded recess surrounding the tube 21 and having a threaded brass packing gland 22 screwed into it and encircling the tube. The inner end of the gland and the opposed inner end of the recess are oppositely tapered and having a packing 23, preferably of lead wool, interposed between them. Said packing is compressed about the insulated tube by screwing the gland, and a closely sealed airtight joint is formed.

The insulation 52 and lead sheathing 21 terminate just within the casing 1, and the conductors 13 separate at this point, said conductors each leading into the bore of one of the insulators 9 and fitting at its end into a socket formed upon a terminal rod 24 and being soldered therein. The terminal rod extends outward from the upper end of the insulator and is threaded. A hood nut 25, preferably of cast brass, is screwed upon the

projecting end of the rod and covers it. Interposed between the end of the insulator and the hood nut is a gasket 26, preferably of vellumoid, and the nut is formed with a flange surrounding the gasket. An aerial lug 27, preferably of cast copper, for the attachment of an outside conductor 51, is clamped upon the hood nut.

The bore of the insulator is materially larger than the diameter of the conductor and that of the terminal rod and provides a surrounding space for the insulation. This space, together with the interior of the casing, is filled with the insulating material 28 in a manner to be described hereinafter. At its outer end, the bore is reduced for a short distance and, at the inner end of the reduced portion, two diametrically opposite notches 29 are formed. A locking pin 30 is passed through the terminal rod 24 and engages in said notches to prevent the rod from turning.

20 The invention provides for the charging of the casing 1 and the assembled insulators with molten insulation in a manner to prevent air spaces or bubbles in the insulation and obtain a uniform density thereof and a complete filling of the casing and insulators around the electrical conduits. This is accomplished by exhausting the air from the pothead to produce an almost perfect vacuum, maintaining the vacuum while the molten insulation is poured, and preventing the 30 introduction of air along with the molten material.

25 The cap 3, at points located at opposite sides of the insulators, is formed with two upwardly projecting nipples 31 which are externally threaded and open into the interior of the casing 1. Each nipple is normally closed by a threaded cap 32 and gasket 33, and when the air is to be exhausted from the pothead preparatory to charging it with molten insulation the cap and gasket 40 are removed from one of the nipples and a suction pump 34 detachably connected thereto. This pump may be of a simple hand operated type. Its connection with the nipple is made through the medium of an elbow 35, a threaded connector 45 sleeve 36 coupling the elbow to the pump and a threaded connector sleeve 37 coupling the elbow to the threaded nipple. Sleeve 37 is provided with an inwardly extending abutment flange 38 which engages an outwardly extending flange 39 formed on one end of the elbow. Interposed between said flanged end of the elbow and the end of the nipple is a disk 40 which is formed of material pervious to air but not pervious to a fluid having the consistency of the molten insulation, 50 and not fusible or destructible by said molten insulation or heat transferred therefrom. Preferably the material of the disk is a hard, porous one, such as pumice stone or unglazed porcelain. The sleeve 37 is tightened to clamp the disk against the nipple and firmly hold the elbow. The provision of two nipples enables the pump to be connected to either side of the pothead, according to the convenience of the workman and the clearance for the pump.

55 For the introduction of the molten insulation, the casing 1 is formed at one side thereof with an outwardly extending nipple 41, externally threaded and opening into the interior of the casing. Normally this nipple is closed by a threaded cap 42 and a gasket 50. When the molten insulation is to be poured, cap 42 and gasket 50 are removed and a supply pipe 43 is connected to the nipple. This pipe leads downwardly to the nipple from a point elevated above the tops of the insulators 75 9, and is provided at its upper end with a funnel

or hopper 44. The pipe is connected to the nipple 41 through the medium of a threaded connector sleeve 45. The latter is screwed upon the nipple and is formed with an inwardly extending flange 46 to engage an outwardly extending flange 47 upon the pipe. Interposed and clamped between the flanged end of the pipe and the opposed end of the nipple is a disk 48 entirely obstructing the entrance to the nipple. This disk is formed of a hard dense material which is capable of excluding air and of being fused by contact with the molten insulating material. Preferably the latter material is a suitable grade of bitumen and the disk is made of solidified bitumen which is fusible at the same temperature as the insulating material.

80 The pump is first operated to exhaust the air from the pothead through the porous disk 40. This, in addition to preparing the pothead to receive the insulation, serves to test the various joints for leakage. When the joints are effectively sealed, an almost perfect vacuum may be produced. A gauge 49 may be connected to the pump to indicate the vacuum. The molten bitumen is poured into the hopper 44, whose capacity is preferably at least equal to the pothead space which is to be filled, after a vacuum or substantial vacuum is produced in the casing. From the hopper, which is elevated sufficiently to provide a good head, the molten bitumen flows down the supply pipe 43 to the disk 48. The latter obstructs the flow so that the molten material is dammed up in the pipe 43, to completely fill the cross section thereof and exclude air. The obstruction of the flow, however, lasts for only a short period as the hot molten bitumen melts away the solidified bitumen disk and opens a passage to the interior of the pothead. Operation of the suction pump may be continued during the introduction of the molten bitumen, any air within the casing and hollow insulators passing out through the porous disk 40. The bitumen is thus free to flow in and completely fill the spaces within the casing 1, the cap 3, the insulators 9 and the nipples 31 and 41. It is prevented from 110 passing through the pump connection by the disk 40. Exhaustion of the air from the pothead and exclusion of air from the entering stream of molten insulation causes the latter to completely fill all of the spaces in the pothead, and when the 115 insulation solidifies it will be uniformly dense and free from air bubbles, spaces or pores. The surrounded conductors within the pothead will therefore be thoroughly insulated and short circuiting to the metal parts of the pothead will be 120 prevented.

125 After the charging of the pothead and solidifying of the bitumen, the nipples 31 and 41 are capped, as shown in Fig. 5, the charging means and vacuum creating means being first disconnected from said nipples.

130 What I claim is:

1. The method of filling free space within an 135 encased joint of an electricity conductor with insulating material in a liquid state which comprises maintaining a suction outlet in said casing closed to passage of said insulating material but open to passage of gaseous material during filling of said space, and admitting said insulating material into the space and subjecting it to suction at said outlet until the space is filled with bubble-free insulating material.

2. The method of charging the free casing space in an encased joint of an electricity conductor with normally solid insulating material,

- which comprises flowing said material in a molten state in a stream to the casing, fusing an entrance for said stream into said casing through the medium of the hot leading end of 5 the stream, and permitting the stream of molten material to flow into the casing through the entrance thus opened. 80
3. The method of charging with normally solid insulating material the free casing space within 10 an encased joint of an electricity conductor, which comprises heating a supply of said material to a molten state, flowing a stream of said molten material from below the surface of said supply to the joint casing, melting open an inlet in the casing for the stream by the hot leading end of the stream, allowing the said stream of molten material to continue to flow from 15 said supply into the casing through the inlet thus opened, restraining the admitted material 20 from being sucked out of the casing, subjecting the interior of the casing and the restrained material to suction during said continued flow of the material into the casing until the free space of the casing is filled with bubble-free molten 25 insulating material, and then allowing the insulating material in said space to cool and solidify. 90
4. The method of filling the free space in an encased joint of an electricity conductor with 30 normally solid insulating material, which comprises keeping the free space open to a supply of said insulating material in a molten state and closed to inflow of free air; and, while so doing, subjecting the free space to suction and keeping 35 it continually closed to outflow of the molten insulating material until no more of the insulating material can flow into said space from the supply. 100
5. The method of charging the free space in 40 an encased joint of an electricity conductor with insulating material in a liquid state, which comprises keeping said space open to a head of said liquid insulating material which bars inflow of 105
- free air into the space, and simultaneously subjecting the space to suction and the fed material to a screening action at an air outlet from 85 said casing to retain in the casing all the liquid material fed thereinto and exhaust air from the casing until the casing is filled with bubble-free liquid insulating material. 95
6. The method of charging the free space of an encased joint of an electricity conductor with molten insulating material, which comprises continuously charging said molten material into 110 said space while both exhausting said space through a gas outlet and filtering the molten material from occluded gaseous material at said gas outlet until no more of the molten material can enter said space, and thereupon allowing the gas-free filling of molten material in said space to solidify. 115
7. The method of filling the free space of an encased joint of an electricity conductor with molten insulating material, which comprises flowing said molten material in a stream from a source of supply to said encased joint, fusing an entrance for the stream to said space through the medium of the hot leading end of said stream, 100 maintaining said stream in sufficient volume to keep said entrance closed to inflow of free air, and exhausting air from said space through an outlet while keeping said outlet constantly closed to outflow of the molten material until no more 105 of the molten material can flow into said space through said entrance, and thereupon shutting off said source of supply of molten material from the encased joint and stopping the air exhausting action on said space. 110
8. The method, as claimed in claim 7, of filling the free space of an encased joint of an electricity conductor with molten material, characterized by the step of exhausting air from the free space of said encased joint through said 115 outlet prior to the fusing of the entrance to said space for said stream of molten material. 120
